(57) **CLAIM**

The ornamental design for a boot cover as shown and described.

DESCRIPTION

FIG. 1 is a front, left, and top perspective view of a boot cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a zipper head.

FIG. 9 is a partial enlarged view of an area labeled 9 in FIG. 1 comprising a drawstring; and,

FIG. 10 is a partial enlarged view of an area labeled 10 in FIG. 4 comprising a zipper head.

The broken lines shown in the drawings are included for the purpose of illustrating portions of the boot cover that form no part of the claimed design.
